PERFORATING DEVICE FOR CHECKS,
DRAFTS, AND THE LIKE

Joseph Moll, Philadelphia, Pa.

Application June 10, 1933, Serial No. 675,269

7 Claims. (Cl. 101—20)

My invention relates to new and useful improvements in devices for perforating or punching figures and characters on checks, drafts, etc., and it consists in the constructions, arrangements and combinations herein described and claimed.

It is an object of the invention to provide a perforating device which is of extreme simplicity both as to construction and operation, and one which may be conveniently carried in the pocket 10 of a user.

It is also an object of the invention to provide a device of this character wherein a multiplicity of dies are detachably associated with a platen member so that the die members may be 15 quickly attached or detached from the platen, thus facilitating the interchange of the dies to accommodate the punching of checks to the amounts desired.

It is a still further object of the invention to 20 provide a punch or perforating device of this kind, constructed in the form of a case, one cover member functioning to contain the platen and attached dies, while the other embodies an anvil which cooperates with the dies to perforate an 25 interposed check upon closing the cover members.

Additional objects, advantages and features of invention will be apparent from the following description and accompanying drawing, wherein

Figure 1 is a top plan view of my check perforating device, in open position.

Figure 2 is a cross section on the line 2—2 of Figure 1.

Figure 3 is an enlarged fragmentary cross section of the case illustrating one of the die members and anvil in operative relation.

Figure 4 is a detail perspective of one of the die members.

In carrying out my invention, I provide a case generally indicated at 10 embodying hingedly connected cover members 11 and 12. These covers 11 and 12 are preferably so shaped as to readily fit in a vest pocket and one of the cover members has fixed thereto a clip device 13, whereby the case may be retained in the pocket, as 45 will be readily understood. The cover members 11 and 12 also include a suitable catch device 14 for maintaining the covers in closed relation, against the tension of the springs 15 of the hinge members 16.

50 The cover members 11 and 12 are each provided with a wall 17—18 respectively, which lie in a plane substantially parallel with the backs of respective cover members 11 and 12, and preferably, a vertically disposed wall 19 is interposed 55 between the respective cover members and the

walls 17—18 for affording stability thereto, all of which is clearly shown in Figure 2.

The walls 17—18 are provided with a plurality of socket members 20 which detachably support die members 21—22. The die member 21 in the present instance represents numerical dies, while the dies 22 represent dies embodying the various letters of the alphabet, and preferably there is more than one complete set of such dies. The dies 21—22 are detachable from their respective 65 sockets 20 and attachable to socket members upon a suitable platen in a manner to spell or set down the amount of the check which is to be perforated, as will now be fully explained.

The platen is represented by the reference 70 character 23 and is shown as a continuous part of the wall 17, and this platen is provided with a plurality of rigidly secured socket members 25, arranged in a single row parallel with the side wall 26 of the cover 11, the sockets 25 being 75 suitably spaced.

The anvil 27 is carried by the cover 12 and extends parallel to the side wall 28 of the cover. The anvil lies flush with the upper edge of the wall 28, as shown in Figure 3, and is preferably 80 resiliently supported throughout its length by cushion blocks 29. The anvil and cushion blocks may be secured in position within the cover 12 by studs or screws 30. The blocks 29 are composed of a suitable rubber composition in order that the 85 anvil may have a slight vertical movement during the perforating operation.

As clearly shown in Figures 1 and 3, the anvil includes a plurality of recesses 31, of like number as the sockets 25, and spaced similarly, so that 90 when the covers 11 and 12 are in closed position each recess 31 will be in opposed relation to one of the sockets 25.

The die members 21—22 include a circular body member 32 having a flat upper face from which 95 there are projected pins 33. These pins are arranged so as to define the numerals or letter desired. From the body 32 there is a ball portion 34 adapted to be received in the sockets 20—25. The sockets 20—25 may be of any of the well 100 known constructions, but in the present instance, I have illustrated a body portion 35 centrally apertured to receive the ball 34 and a keeper spring 36 adjacent the entrance of the aperture. Other forms of balls and sockets may be found 105 equally desirable.

It will be noted from a consideration of Figure 3 that when the cover members 11 and 12 are brought to their closed positions, the faces of the die members secured in the sockets 25 stop short 110

of the anvil 27 approximately the thickness of a check to be perforated, and consequently the only portion of the dies which may penetrate or perforate the check are the pins 33 and this action is further insured by the resilient mounting of the anvil 27.

In use, the operation will be substantially as follows, assuming that a check for \$10.50 is to be perforated, using the alphabetical dies 22.

10 The catch 14 is first released, allowing the cover members 11—12 to swing to their full open positions. We now detach the die embodying the first letter of the sum above, which is the letter "T" and insert the ball 34 thereof in the first 15 socket 25 of the platen 23; the next letter being "E" this die is removed from its socket 20 and is attached to the socket 25 next adjacent the letter "T" which had been previously attached. This procedure is followed until the amount has been 20 set up in the sockets 25. After the dies have been thus placed, the check 37 (see Fig. 3) is laid upon the anvil 27 and the covers 11 and 12 then 25 swung into closed position. The check is, of course, laid upon the anvil so that the perforations will occur upon the proper line. It will be readily seen that upon closing of the covers, the pins of the dies will perforate the paper of the check, so that when the check is removed, the amount of the check will be punched in the paper, 30 clearly legible but obviously preventing alterations thereto.

The check may be perforated as well by the use of the numerical dies, it being only necessary to select the desired dies and inserting them in their 35 respective sockets of the platen.

While I have described the device as employed for punching checks, drafts, or the like, the invention is not so limited, as the device may be readily employed in other situations, such as 40 punching or perforating the initials of a buyer of a hat, in the sweat-band of a hat.

I am aware that various modifications of the device may readily be made and I therefore do not confine myself to the exact construction 45 shown and described and consider as my own all such modifications as fairly fall within the scope of the appended claims.

I claim:—

50 1. A perforating device of the character described comprising a pair of hingedly connected cover members, a platen carried by one of said members, perforating die members carried by said platen and a resiliently supported anvil carried by said other cover member cooperable with said dies upon movement of said cover members to closed positions.

55 2. A perforating device of the character described comprising a pair of hingedly connected cover members, a platen carried by one of said

60

75

members, detachable perforating die members carried by said platen, and a resiliently supported anvil carried by said other cover member cooperable with said dies upon movement of said cover members to closed position.

80

3. A perforating device of the character described comprising a pair of hingedly mounted cover members, a plurality of socket members carried by each of said cover members, perforating die members detachably associated with each of said socket members, a platen carried by one of said cover members, and having a single row of longitudinally spaced socket members for reception of selected first named die members, and an anvil carried by said other cover member, said anvil having recesses, spaced corresponding to said longitudinally spaced socket members, whereby the dies of said sockets and recesses will be brought into registration upon closing movement of said cover members.

85

4. A perforating device comprising a pair of hingedly connected members, a platen carried by one of said members and including a plurality of socket members arranged in a longitudinal row, die members detachably supported by certain of said socket members, an anvil carried by said other member, said anvil having a plurality of recesses arranged in a longitudinal row and adapted to register with said die members upon closing movement of said hingedly connected members.

90

5. A perforating device comprising a pair of hingedly connected members, a platen carried by one of said members and including a plurality of socket members, each socket having an aperture and retainer spring, die members detachably supported by said sockets, said die members having a ball member insertable within said sockets, and a resiliently supported anvil carried by said other member and adapted to register with said die members upon closing movement of said hingedly connected members.

95

6. A pocket check perforating device comprising hingedly connected cover members, said cover members including respectively a platen and a resiliently supported anvil perforating means carried by said platen, and said anvil having recesses cooperable with said die members upon closing of said covers to perforate a check interposed therebetween.

100

7. A perforating device of the character described comprising a pair of hingedly connected cover members, a platen carried by one of said members, die members carried by said platen, an anvil carried by said other cover member cooperable with said dies upon movement of said cover members to closed position, and resilient means associated with said platen and anvil.
